UNITED STATES PATENT OFFICE.

THOMAS CHAMBERS MILLS, OF LONDON, ENGLAND.

MACHINE FOR REMOVING HAIRS FROM FUR SKINS.

SPECIFICATION forming part of Letters Patent No. 754,381, dated March 8, 1904.

Application filed August 3, 1903. Serial No. 168,030. (No model.)

To all whom it may concern:

Be it known that I, THOMAS CHAMBERS MILLS, a subject of His Majesty the King of Great Britain, residing at London, England, have invented a certain new and useful Improvement in Machines for Removing Hairs from Fur Skins, of which the following is a specification.

This invention relates to improvements in the means for "pulling" or "plucking" rabbit or other suitable fur skins—that is, removing the hairs technically known as "kemps" therefrom without injuring the fur, which is also cleansed from what is known as "nature," a kind of grease found to occur therein, particularly with the fur skins of some animals, such as rabbits or hares, and which grease depreciates the value thereof owing to the loss experienced through it when the skin is put to use for manufacturing purposes. Although machines have hitherto been used for removing such hairs, they have only been capable of imperfectly plucking out the long ones projecting above the fur-surface, whereas by this invention both the long and short hairs are removed without destroying the fur.

To enable this invention to be clearly understood, reference is made to the appended drawings, in which—

Figure 1 is a sectional side elevation, and Fig. 2 a front elevation, of the machine. Figs. 3 and 4 are enlarged details illustrating the operation of a sliding table and connected parts hereinafter described. Figs. 5 and 6 show alternative forms of surfaces for the plucking-drum hereinafter described.

The sides of standards 1, connected together at the back and lower ends by plates 2 3, respectively constitute the framework of the machine, at the front of which is loosely mounted a spindle 4, provided with a hand-lever 5 and arms 6, the latter being connected at their outer ends by adjustable rods 7 to a sliding table 8, that can be reciprocated on the slides 9, formed integrally with the sides 1, or they may be plates attached thereto. A rubber-covered spindle 10 is supported in brackets above the inner edge of the table 8, while projecting forward therefrom is a simi-

lar spindle 11, capable of passing between fluted rollers 12 and 13, that are rotated in the same direction by means of toothed wheels 14 15 16 and which receive motion by band and pulley wheels 17 and 18 from the driving-shaft 19, on which is also mounted a pulley-wheel 20, connected to a similar wheel 21, fixed on the spindle 22 of the plucking-drum 23. This drum consists of end plates 24, with pins 25 arranged between same and near the outer circumference for the purpose of holding circular rubber sleeves 26, which are pressed outward by a central packing block or sleeve 27 on the spindle 22 and compressed so that a number of projecting curved resilient surfaces are formed thereby. Other arrangements may, however, be employed for compressing and pressing outwardly these rubber sleeves or the blocks hereinafter described so long as the object in view—viz., the presentation of suitable resilient surfaces—is retained.

At the ends of the spindle 22 are loosely mounted brackets 28, connected at their upper ends to form a frame, the upper bar 50 of which carries a lug 29, forming a nut for a long screw 30, loosely attached to the projection 31, carried by one of the standards 1, and which screw enables the frame which pivots on the spindle 22 to be rocked or given a backward or forward position. For holding the frame in the position desired the side brackets 28 of same have a curved or quadrant slot 32, through which pass bolts and nuts 33 to lock them to the standards. The brackets 28 also have slots 34 to take the ends of a bridge-piece 35, that carries in brackets at its ends a spindle or equivalent part 36, provided with or formed as a fluted metal or a fluted or plain rubber sleeve or part, so that it can be raised or lowered by a screw 37, passing through the part 50, such screw having a nut in a hand-wheel 38. In addition to this set-screws 39 pass through the part 50 and abut on bridge-piece 35 to act as supports or steady-ing devices for the ends of the bridge 35 in conjunction with the screw 37. The screws 39 may be locked in the desired position by nuts 51.

At the back of the machine a fan 40 is arranged between suitable supports to take off the hair and dust.

In the treatment of some skins it may be necessary to have more than one kind of surface for the plucking-drum, so that they pass through a series of operations employing either one or both forms hereinafter described in conjunction with the previously described.

- 10 As an alternative form of flexible plucking-surface the arrangement shown in Fig. 5 may be used: This consists of an endless leather band 41, having projecting flexible loops or ridges 42 formed thereon, of any suitable material, such as leather or cord, which is placed over the drum 23 and the rubber sleeves 26 or over any suitable kind of supporting-drum and is kept tight by a spindle 43, which may be carried in bearings 44 in the standards 1, 15 as shown, or be a loose spindle. By the use of this band 41 with the loops or ridges 42 in conjunction with the fluted or plain spindle 36 the fur may be plucked and polished without the weight thereof being reduced when 20 the action of the sleeves 26 might be unsuitable for the class of fur treated.

In the alternative form of drum shown in Fig. 6 every other sleeve 26 is the same, as in Figs. 1 to 5; but interposed between them are 25 blocks or sleeves of rubber or other suitable material 45 of more or less rectangular shape in cross-section, with the outer surface inclined to form a projecting flexible ridge 46 to cause a stronger action on the skin, which 30 is useful in the case of old or coarse skins or under other conditions and also serves to polish the fur thereof. The blocks or sleeves 45 may be held by the spindles 25, as shown, and if more flexibility is desired they may have 35 enlarged openings 60 formed therein, through 40 which the spindles 25 pass, as shown on the right-hand side of Fig. 6.

The adjustable spindle 36 may be provided, as stated, with interchangeable fluted metal 45 or fluted or plain rubber sleeves, so that the metal sleeve can be used first to remove the hairs by its hard gripping action in conjunction with the drum 23 or the band 41 and then a rubber sleeve be substituted therefor to give 50 a finish to the fur, while a different effect may be given to the fur by the use of the drum 23 or band 41 and the rubber sleeve alone. The spindle 36 is made adjustable, so that the machine can be used for plucking skins having 55 hairs of different lengths, for which purpose it is brought forward or backward by the screw 30 for long or short hairs and also lowered or raised by screw 37 for tight or easy gripping.

60 The operation of this invention is best shown in Figs. 3 and 4, where when the machine is running the plucking-drum 23 and rollers 12 and 13 are rotated, as indicated by the arrows. The table 8 is normally in its rearward position, as shown in Fig. 3, and if a skin is held

down in front of said table with the fur-surface toward said rollers 12 13 and the table 8 moved forward by means of hand-lever 5, arms 6, and rods 7 on its slides 9, as shown in Fig. 4, the rubber-covered spindle 11 will 70 bend and press the skin between the rollers 12 13 onto the surface of the plucking-drum, which being rapidly rotated beats the fur-surface up against the fluted metal or rubber sleeve on spindle 36, whose gripping-surface 75 enables the hairs or kems to be plucked out by the striking action of the sleeves 26 against the metal flutings or the rubber flutings or plain surface without injury to the fur, which is kept in an open condition by the 80 bend imparted to the skin by the rollers 11, 12, and 13. The rotation of the roller 13 draws in or feeds the skin, and that of the roller 12 withdraws the skin in a vertical direction, as shown in Fig. 4, for which purpose it acts against the rubber-covered spindle 10 of the table 8.

I have before proposed to present a skin in a bent or open condition to a beating-roller by pushing it forward by means of a spindle 90 between feeding-in and drawing-off rollers, and I do not broadly claim such as my present invention.

What I claim is—

1. In a machine for removing hairs from 95 fur skins, and in combination, a plucking device comprising a series of curved flexible beating-surfaces having an air-space on their rear side, means for holding such flexible surfaces at their inner ends only so that they are 100 resilient from their base outwardly, means for rotating the same, and a part in conjunction with which such resilient surfaces work.

2. In a machine for removing hairs from fur skins, and in combination, a series of 105 resilient beaters composed of curved surfaces, of flexible material having an air-space on their rear side whereby their natural elasticity is increased, means for carrying and rotating the same, and a spindle in conjunction with which the resilient beaters work.

3. In a machine for removing hairs from fur skins, and in combination, a plucking device having yielding plucking-surfaces, means for rotating the same, a bracket pivoted centrally of the plucking device, a spindle with which such device co-operates, and a part carrying such spindle and adjustable on said bracket whereby the spindle can be moved around the plucking device, and also be moved 110 toward and away from the same.

4. In a machine for removing hairs from fur skins and in combination, an endless band, flexible loops carried by the same, means for carrying and rotating said band, and a spindle 115 in conjunction with which the loops work.

5. In a machine for removing hairs from fur skins and in combination, an endless band having a looped surface, means for carrying and rotating said band, a supporting-drum 120

130

for the band, a spindle, means for adjusting same, and means for presenting, feeding in and withdrawing the skins to and from the looped surface and spindle.

5 6. In a machine for removing hairs from fur skins and in combination, a table, means for reciprocating same, rubber-covered spindles 10, 11, carried by said table, a plucking device having yielding plucking-surfaces, a spindle to coöperate with said plucking-surfaces, means for vertically, forwardly and rearwardly adjusting such spindle, feeding-in and withdrawing rollers, and means for carrying and rotating same.

15 7. In a machine for removing hairs from

fur skins and in combination, a table, rubber-covered spindles 10, 11, carried by said table, a plucking-drum, means for rotating same, flexible rubber beaters carried by same, a fluted spindle, feeding-in and withdrawing 20 rollers, and means for carrying and operating same.

In testimony whereof I have hereunto set my hand in the presence of two subscribing witnesses.

THOMAS CHAMBERS MILLS.
